JAMES CAMROD LEDBETTER, OF NEW YORK, N. Y., ASSIGNOR TO THE PROSPERITY COMPANY, INC., OF SYRACUSE, NEW YORK, A CORPORATION OF NEW YORK

GARMENT OR IRONING PRESS

Application filed July 28, 1928. Serial No. 295,951.

This invention relates to pressing machines and more particularly to garment presses and laundry or ironing presses.

An object of the invention is to produce a press having wide opening jaws, one of which has a compound motion including a laterally forward and backward motion and a vertical compressing action to produce jaw compression on the work between the jaws.

10 A further object is to produce a press having wide opening jaws, say of the type wherein in the buck or lower pressing member or jaw is ordinarily stationary while the other pressing member, say the head or upper jaw is movable; and the jaw opening action is wide to afford a clear view of the buck so the work may be easily placed thereupon.

Though the invention is susceptible to being converted into many forms, the accompanying drawings show one example of the press serving to illustrate the principles involved and wherein:

20 Figure 1 is a view of the press in closed position with the jaws under compression; and Figure 2 is a side view of the press with the jaws in open position and ready to receive the work.

25 In carrying out the purposes of this invention there is provided an upright swing link pivoted on its lower end in a frame under the jaws and attached at its upper end to the head jaw. In this way no counterbalance weights are employed. Improvements in operating means to produce jaw compression as well as regulating means to vary the jaw pressure forms a part of the invention.

Any suitable press frame 4 is employed which may carry one stationary jaw, as the buck 5, together with a table 6. A head supporting arm or lever 7 is pivoted in the frame at 8 and any suitable means such as a spring 9 is arranged to normally urge upwardly the lever 7 so as to separate the jaws for release of the compression from the work and followed by opening motion as will be explained.

40 A head or jaw support swing link 11 is pivoted at 12 on the arm 7 and extends rearwardly from the frame and extends vertically upwardly and then forwardly over the jaw 5 where the head support 11 forms a bracket to

mount a handle 13 by which the operator pulls a head 14 forwardly to closed position over the buck 5. The head 14 is attached in any suitable way to the upper horizontal portion of the vertical or upright swing link 11. 55

There is shown a stop carried on the frame 4 to engage a suitable portion of the swing-link-head means 11—14. To this end a cap screw or other means 16 is screw threaded into the frame or into the upright 11 as the 60 case may be. By properly adjusting the cap screw 16, the jaws 14 and 5 are caused to properly align one over the other so that the head comes to rest in its forwardly limited position in registration with the buck 5. The 65 adjustable means 16 therefore provides a stop for the head-carrying swing link 11 and which is at the same time adjustable.

70 Operator-actuated means are provided to produce jaw compression after closing the press. An example of this operating means is shown in the form of a toggle or pedal mechanism wherein a pedal 17 is integrally formed with an arm 18 to make a bell crank 17—18 which may for convenience be pivoted at 12. The bell crank arm 18 in fact comprises one link of the toggle 18—19, the two links of which are pivoted together at 20 and the upper end of the toggle being pivoted at 21. When the pedal 17 is down, the toggle 80 18—19 rests in straight line position or its center 20 is in slightly over-straightened position to lock the jaws together under compression. When the pedal 17 is up the toggle 18—19 is broken to relieve the jaw compression and to permit jaw separation which results when the head 14 is swung rearwardly to expose the buck. A stop is provided to limit the forward straightening action of the toggle 18—19 and may comprise a hand adjustment screw 19a mounted in a bracket 4a 85 carried on the toggle.

90 The upper end of the toggle 18—19 is pivotally swung on the frame 4 and therefore has a normally stationary pivotal support 95 while the lower end of the toggle swings at 12 on the support arm 7 and thus has a movable support. Toggle adjustment means is provided by which the upper end of the toggle 19 is adjustably carried on the frame and 100

is moved vertically in relation to the frame 4, the result of which is to similarly adjust the upright 11 by which jaw compression is regulated to a greater or less degree.

5 An example of the adjustment means comprises a worm wheel 23 engaging a worm 24 fixed to a shaft. The shaft 25 is journaled in the frame 4 and has a hand wheel 26 on the outer end thereof under the table 6 10 convenient to the reach of the operator. The worm wheel 23 is fixed to the shaft 21 and a cam 27 is fixed to the shaft 21. The cam 27 is journalled in a bearing formed in the upper end of the toggle 19. In other words 15 the toggle swings from the cam 27. The operator turns the hand wheel 26 to rotate the cam 27 to adjustably move the upper end of the toggle in vertical relation to the frame 4. Since the upper end of the toggle swings on 20 the cam 27, it follows that by moving the cam 27 upwardly thru the agency of the hand wheel 26, the lower pivot 12 is correspondingly elevated to provide more clearance and less pressure between the jaws 5 and 14. By 25 rotating the cam 27 downwardly the opposite result is obtained and greater compression is produced.

The toggle pivot points 21 and 12 may be arranged vertically under the buck 5. If desired, the two pivot points 21 and 12 are disposed in vertical alignment in the plane of the mean longitudinally center of the jaws when closed or thus arranged in that relation to the stationary buck 5. The jaw compression regulating means 26-27 is mounted in the upper part of the frame under the table and hence high above the floor where these movable parts remain clean. The adjusting mechanism includes relatively few parts and 40 is simple in construction.

In operation, the work is spread upon the buck 5 and the operator draws the head 14 forwardly, whereupon he depresses the pedal 17 which over straightens the toggle 18-19 45 thereby delivering a powerful downward thrust on the lever arm 7 and consequently drawing downward on the upright head swing link 11 to produce jaw compression between the pressing members 14 and 15.

50 A kickoff or release pedal 29 is pivoted on the frame at 30 and its inner end 31 engages the under edge of the compression pedal 17 when the machine is under pressure. By depressing the kickoff 29, the pedal 17 is raised and hence the toggle 18-19 is broken rearwardly and the spring 9 lifts up the operating means comprising the several parts and hence lifts the head so the latter may fall 55 back to open position.

The press opening and closing motion is by lateral action, while compression and release thereof is by vertical action. The head therefore swings directly back out of the 60 way rather than by a rising action. The ma-

chine is easy to operate and is simple in construction.

What is claimed is:—

1. In a press, a frame and cooperating press jaws, operating means to open and close the 70 jaws, including an upright having its upper end attached to one jaw, an arm pivoted in the frame and on which the lower end of the upright is pivoted, a pedal pivoted on the arm, and means operated by the pedal to depress the arm to draw down on the upright and produce jaw compression.

2. In a press, a frame and a cooperating press head and buck, an arm pivoted in the frame, an upright pivoted at its lower end 80 on the arm and curved out of the frame at the rear thereof and reaching past the rear edge of the buck extending horizontally above the buck and attached to the head to actuate the same, a bell crank pivotally supported on the 85 arm and including a pedal and an upstanding link, and another link the upper end of which is pivoted on the frame and the lower end of which is pivotally connected with the link of the bell crank.

3. In a press, a frame and a cooperating head and buck, a head-operating member including a horizontal portion attached to head, an upright portion extending downwardly into the frame and under the buck, an arm pivoted in the frame and the head-operating member being pivotally supported at its lower end on the arm, a vertically extending toggle the upper end of which is pivoted in the frame and the lower end of which is pivotally connected with the arm on the same pivot which supports the lower end of the head-operating member, and a pedal means pivotally supported on the arm on the same pivot with the toggle and member and having connections with the toggle to actuate the same.

4. In a press, a frame and a cooperating head and buck, a horizontal arm pivoted in the frame and means to urge the arm upwardly, a pedal pivotally supported on the arm below the center of the buck and having an upstanding link, another link connected with the first link and the upper end thereof being pivotally supported on the frame thereby forming a toggle which is actuated by the pedal, and an upright attached to the head to actuate it and extending around the buck and into the frame and pivotally supported by the pedal pivot on the arm.

5. In a press, a frame and cooperating 120 press jaws, operating means including a toggle to actuate one of the jaws in a lateral back and forward direction to open and close the press and to execute a vertical motion for producing and releasing jaw compression, said operating means including a vertical upright which is swingably mounted in the frame, an adjustable-stop means cooperating with the frame and upright where- 125 by the forward motion of the jaw aforesaid 130

may be adjusted to secure jaw alignment when the press closes and compresses, an adjustable pivot carried on the frame and on which one end of the toggle is supported, and means at the front of the press to set the adjustable pivot to vary the jaw compression.

6. In a press, a frame and cooperating press jaws, operating means to actuate a jaw to open and close the press and produce jaw compression, said operating means including a vertical toggle each end of which is pivotally carried on a movable pivot, manually adjustable means cooperating with one of the movable pivots to adjust the same to vary 10 the jaw compression, an upright having its lower end pivoted on the lower pivot and its upper end reaching around and above the upper pivot and attached to one of the jaws, an arm having one end portion pivoted on 15 the frame and in which the lower pivot is mounted, and a resilient connection between the other end portion of the arm and the frame.

7. In a garment or laundry press, a frame, 20 cooperating press jaws carried thereon including a stationary buck and a swingable head, a toggle vertically disposed in the frame having its upper end supported on a pivot directly under the buck, a horizontal 25 arm having its rear end pivotally mounted on the rear of the frame, a resilient connection between the front end of the arm and the frame, a pivot carried by the arm between the spring connection and frame pivot point 30 and the lower end of the toggle being supported on the last named pivot, an upright 35 having its lower end carried on the last named pivot and hence on the arm, said upright curving rearwardly and upwardly from 40 the frame and reaching behind the jaws and bent forward horizontally above the head 45 and attached thereto, and said toggle being formed of operable links the lower one of which includes a horizontal pedal projecting from the frame at the front of the press.

8. In a press, a frame and cooperating press jaws, a swingable upright having its upper end attached to one jaw, a single pivot means carrying the upright for independent 50 swingable motion thereon, an arm movably supported on the frame to support said single pivot means, said single pivot means having a limited substantially vertical movement, a pedal freely journalled on the single pivot 55 means and rotatable independently of the swingable upright, and means operated by the pedal to depress the single pivot means to draw down on the upright and produce jaw compression.

60. 9. In a press, a frame and cooperating press jaws, a swingable upright having its upper end attached to one jaw, a single pivot carrying the upright for independent swingable motion thereon, means on the frame 65 carrying the single pivot, said single pivot

having a limited substantially vertical movement, spring means urging the single pivot upwardly, a pedal freely journalled on the single pivot and rotatable independently of the swingable upright, and means operated 70 by the pedal to depress the single pivot to draw down on the upright and produce jaw compression.

In testimony whereof I affix my signature. JAMES CAMROD LEDBETTER. 75
